ABSTRACT OF THE DISCLOSURE

In a process for the production of olefins suitable for conversion to detergent alkylates via the cracking of heavy petroleum fractions, the fractional distillation of the fraction thus-cracked and the separation therefrom of a fraction rich in straight-chain olefins, the improvement which comprises the cracking of a heavy petroleum fraction boiling within the range of from about 300° C. to 600° C. and containing more than about 35% by weight aromatics and less than about 15% by weight straight-chain hydrocarbons, the separation therefrom of a second fraction rich in straight-chain olefins having from 8 to 15 carbon atoms and having a distillation range of from about 120° C. to 300° C., and the recovery of such straight-chain olefins having from 8 to 15 carbon atoms from said second fraction by treating the same with urea to selectively form adducts of urea with said olefins, separating these adducts and thence decomposing the same.

The present invention relates to a process for the preparation of alkylated aromatic hydrocarbons and, more particularly, to alkylbenzenes suitable for the production of detergents susceptible to biological degradation.

It is known in the art that the preparation of synthetic detergents from alkylaromatic hydrocarbons, using branched chain olefins for the alkylation of the aromatic hydrocarbons, gives rise to intermediate products for the preparation of detergents having excellent surface-active characteristics albeit undesirable compounds are also formed inasmuch as they are not biologically degradable or are biodegraded only after long periods of time.

Consequently, various methods have been developed for preparing olefin mixtures with a linear chain suitable for use in the alkylation of aromatic hydrocarbons so as to obtain alkylaromatic hydrocarbons perfectly suited for the preparation of synthetic detergents which are totally biodegradable within a set period of time.

In the light of such methods, olefins suited for the preparation of alkylated biodegradable detergents are obtained via the cracking (pyrolysis) of hydrocarbon mixtures, such as paraffinic waxes having special chemical and physical properties, or by cracking "gas oil" containing aromatic and naphthenic hydrocarbons at lower levels.

Such a procedure, however, is quite expensive because of the high cost of the hydrocarbon mixture to be subjected to cracking, or in relation to the particular purification operations of the high-boiling hydrocarbon mixtures which, in themselves inexpensive, do, however, effect olefins in such quantities and quality as to satisfy the necessary properties only if purified by very burdensome processes.

Accordingly, it is an object of this invention, to provide a process for the preparation of alkylaromatic hydrocarbons suitable for the production of biodegradable detergents, and according to which process the linear olefins

necessary for the alkylation are obtained from heavy fractions of petroleum of any composition and containing any level of aromatic and naphthenic hydrocarbons.

These and other objects are achieved according to this invention, which consists of a process for the preparation of alkylaromatic hydrocarbons suitable for the production of biodegradable detergents by using as starting materials (raw material) heavy fractions of petroleum of any composition with a boiling point range of from 300°—600° C. such as gasoil, fuel oil and so on, submitting said heavy fractions to cracking under such conditions as to bring the content of long-chain monoolefins in the resulting hydrocarbon mixture to a maximum, separating by fractional distillation from said mixture a fraction comprising, *inter alia*, linear olefins having from 8 to 15 carbon atoms, subsequently treating this fraction with urea in a solvent for urea and, ultimately, in the presence of a diluent for the hydrocarbons, in such manner that the urea selectively forms an adduct with the linear chain olefins, subsequently decomposing said adduct in the presence of an aromatic hydrocarbon while maintaining the linear olefins in solution after separation of the urea by precipitation, and, after having previously added conventional Friedel-Crafts catalysts, directly effecting the alkylation reaction between said aromatic hydrocarbon and the linear chain olefins which are kept in solution.

According to the process of the present invention, alkylaromatic hydrocarbons are obtained in very high yields and are suitable for the production of biodegradable detergents starting from petroleum fractions of compositions that, from an economic point of view, discourage their use according to the methods employed so far, that is, for example petroleum fractions that, because of a very low content of linear hydrocarbons, even lower than 15% by weight, and a very high content of aromatic compounds, even higher than 35% by weight, would not profitably be used for this purpose.

The alkylaromatic hydrocarbons obtained according to the process of this invention lead, through sulfonation with oleum or SO_3 and subsequent neutralization, to alkylated detergents which are totally biodegradable within a set period of time and which, additionally, display superior characteristics in regards detergency and product quality.

More particularly, this invention relates to a process for the preparation of alkylaromatic hydrocarbons suitable for preparing detergents which are biodegradable, and which process characterizes itself by the following steps:

(a) Steam cracking a fraction of petroleum at a distillation temperature within the range of from 300° to 600° C., preferably between 350° and 550°, this petroleum fraction being obtained via vacuum distillation of the residue of the atmospheric distillation of the crude oil (topping).

These fractions of petroleum may be of any origin and may have any composition; for example, content of aromatic hydrocarbons may even be higher than 30%—35% by weight, and the total content of non-linear hydrocarbons (for example aromatics+naphthenes+iso-paraffins) may be higher than 85% by weight. The cracking conditions are chosen in such a way as to maximize the content of the linear mono-olefins.

The preferred conditions for the steam cracking comprise a temperature ranging from 550° to 650° C., a pressure of between 1 and 5 atm., a weight ratio between the load of hydrocarbons and the fed steam varying between 8 and 12, and a feeding velocity defined as space velocity (that is the quantity (expressed in kg.) of load+vapour which in a unity of time (1 hr.) flows through a volume unit of the cracking coil (expressed in l.)) comprised between 1.0 and 7.0.

Upon cracking these fractions a hydrocarbon mixture is obtained which contains linear and branched chain cyclic mono- and polyolefins and aromatics with contents thereof varying according to the cracking conditions and to the composition of the starting mixture.

(b) The mixture emanating from the cracking is subjected to fractional distillation to obtain a fraction with a distillation range of from 120° to 300° C., comprising, inter alia, olefinic hydrocarbons of from 8-15 carbon atoms, preferably a fraction with a distillation temperature range of from 160°-260° C., and comprising the olefinic hydrocarbons of C₁₀-C₁₄.

(c) This fraction is then subjected to an extraction treatment with urea by means of which the linear hydrocarbons (mainly the normal olefins) are separated from the rest of the mixture, subsequent to the formation of an adduct with the urea.

The extraction with urea consists in extracting the hydrocarbon fraction, which fraction was separated from the mixture coming from the cracking, with a quantity of urea equal to 33.5-5 parts by weight of urea for one part by weight of product that may be transformed into an adduct, using a solvent for urea, preferably alcoholic such as, for example, methanol, and in a quantity equal to 0.5-1.2 parts by weight of alcohol per one part by weight urea.

Furthermore, when the quantity of linear hydrocarbons to be extracted by urea exceeds 20-30% by weight of the total weight of the hydrocarbon fraction to be treated, it is convenient to add a diluent for the hydrocarbons sufficient for restoring the percentage of linear hydrocarbons to the indicated values.

As diluents there may be used those substances that are miscible with hydrocarbons, that do not form adducts with urea and that do not decompose the adduct formed by the linear hydrocarbons, for example, branched, chlorinated, aromatic hydrocarbons and the like.

The extraction with urea is carried out in a mixer or other similar equipment that affords intimate contact between the two phases that are formed: the solid phase, formed by the urea n-olefine adduct and the unreacted urea, and the liquid phases formed by all the rest, that is by the remaining non-linear hydrocarbons, saturated as well as unsaturated, cyclic and aromatic, together with solvent for the urea.

The reaction to form the urea n-olefine adducts is carried out at temperatures generally between from about 0° and 35° C. Good results are obtained when operating at temperatures between about 0° and 25° C. at contact times varying from about 20 to 60 minutes depending upon the degree of stirring.

By effecting the extraction of the linear olefins with urea subsequent to the cracking, as has just been described another great advantage is achieved, which advantage represents a peculiarity of the process according to this invention. As a matter of fact, by operating in such a manner, a considerable portion of the heavy isoparaffins present in the charge at the cracking stage is transformed into linear long-chain olefins, however, by carrying out the extraction of the linear hydrocarbons before cracking, the isoparaffins would be for the most part eliminated from the charge and thus would be lost for all intents and purposes herein.

According to the process of this invention, said isoparaffins being transformed into linear olefins and subsequently extracted with urea, same can be used with a view to the economy of the process by contributing to the increase of the final yield.

The product of the urea n-olefin reaction is purified through suitable washings and filterings and is then decomposed in the presence of a suitable solvent for the olefins by heating at a temperature of from 50-80° C., with stirring, for a period of time generally around 30 minutes. Many substances may be used as solvents for the olefins; particularly suited for this purpose are the

aromatic hydrocarbons such as benzene because, such being the case, there can be directly obtained the mixture of n-olefins dissolved in the aromatic hydrocarbons, which, in the presence of the Friedel-Crafts catalyst, directly yield the alkylaromatic hydrocarbons.

Upon decomposition of the adduct there is obtained n-olefins dissolved in solvent and, on the other hand, urea which can be reused for forming the adduct with other linear olefins.

(d) The mixture of linear olefins also comprising the aromatic hydrocarbon used as a solvent for the olefins in the decomposition of the adduct, is fed into the alkylation apparatus, into which there is also introduced an alkylation catalyst of the Friedel-Crafts type, such as, for example, AlCl₃.HCl, BF₃.HF or HF. Of course, the quantity of aromatic hydrocarbon must be equal (if it is the case by a subsequent addition) to the quantity required by the alkylation reaction, i.e., the molar ratio of aromatic hydrocarbon to olefin may vary from between about 4:1 to 8:1.

There occurs in the alkylation apparatus the formation of a mixture of alkylated aromatic hydrocarbons in which the length of the alkyl chain varies depending on the composition of the mixture of linear olefins used as the alkylating agent.

By operating according to the process of this invention, mono or dialkyl substituted aromatic hydrocarbons are obtained wherein over 95% of the products have a linear chain.

(e) The fraction of monoalkylates, separated by fractional distillation from the alkylation mixture and from which has already been recovered excess aromatic hydrocarbon, is subjected to sulfonation with SO₃ or with oleum under conditions well known to those skilled in the art.

The sulfonic acid thus produced is then neutralized with sodium or potassium hydrate, ammonium hydrate, amines, amino-alcohols, etc., so as to effect a paste or a liquid to which can be directly added additives and other constituents necessary for the formulation of commercial detergents.

The detergent formulations, both in powder form or as a liquid, which are prepared by taking as a base the alkylaryl-sulfonates obtained according to the process of this invention may contain additives that are normally incorporated in conventional commercial products, for example, they may contain other compounds of superficial activity, tripolyphosphates, optical bleaching agents, hydrotropes, foam-promoters, foam-inhibitors, foam-stabilizers, perfumes, corrosion-inhibitors and so on.

For example, a typical formulation may consist of the following components:

	Percent
55 Active substance (sodium alkylbenzenesulfonate)	25
Sodium sulfate	28
Tripolyphosphate	40
Sodium silicate	5
Carboxymethylcellulose	2

60 The active substance is formed from a mixture of alkaline alkylbenzenesulfonates differing from each other in the lengths of the linear chains attached to the benzene rings.

In order to determine the degree of biodegradability of the detergents produced according to the process of this invention, the test selected was that prescribed by German law. (Degree of the Biodegradability of detergents in washing or cleaning products, of Dec. 1, 1962, published in the Official Gazette of the German Federal Republic, part I, No. 49 of Dec. 12, 1962, page 698.)

As is generally known, the official rules relating to the testing prescribed by the aforesaid German decree on biodegradability are very strict, and, thus, they offer with greatest safety the best proof of the excellent character-

istics of biodegradability of the detergents prepared according to the process of this invention.

The results obtained from these tests demonstrate that the detergents obtained with the process of this invention have actually a biodegradability greater than 90%.

For even greater safety the biodegradability test was carried out with the same method on the active substance (mixture of monoalkylarylsulfonates) without all the components present in the formulation. Again the biodegradability turned out to be greater than 90%.

For determining the biodegradability, the active substance was subjected to the so-called "River Water Test" vis-a-vis the usual commercial products and again the detergents obtained displayed excellent biodegradability.

The "River Water Test" is a control method proposed by the British Institute, "Committee on Methods for the Analysis of Trade Effluents" (see "The Analyst," volume 82, page 826, 1957).

This method consists in preparing a solution of detergent of very low concentration (around 10 parts by weight per million) in river water in which the absence of anionic detergent has been previously ascertained, and in determining the residual concentration of non-degraded detergent at certain set intervals of time.

The invention will be further illustrated by the examples following hereinunder, which are merely intended to be illustrative and in no way limitative.

The examples are characterized by four processes that differ from each other by whether or not they include the phase of separation of the hydrocarbons with a linear chain: by the type of separation chosen, as an example, i.e., separation by solvent or by urea; at which point of procedure this latter type of separation is carried out, i.e., whether the separation by urea is carried out before or after the steam-cracking phase. In the various processes, the operations follow the order indicated in the following scheme:

- (1) (No separation) → steam cracking → Alkylation
- (2) Separation by solvent → steam cracking → Alkylation
- (3) Separation by urea → steam cracking → Alkalation
- (4) Steam cracking → separation by urea → Alkylation

The first three processes are given for purposes of comparison.

In all cases, the biodegradability test is effected on the end product, and from the examples that follow, it will be seen that in order to obtain arylalkyl detergents having a maximum biodegradability, and starting from products of little commercial worth, i.e. with a low content of linear hydrocarbons, the best process will consist in effecting the separation by urea in the phase immediately following cracking.

The results of the tests illustrated by the examples and the numerical data relative thereto are all recorded in Table 1.

In all examples, the quantities are expressed in parts by weight, except where otherwise indicated.

Example 1

A definite quantity of heavy gasoil obtained by vacuum distillation of the residue of a topping of Libian crude oil and which had the following characteristics:

Distillation range	° C	350-550	70
Refraction index N_D^{20}		1.4848	
Composition:			
n-Paraffins	percent	13.6	
Isoparaffins and cycloparaffins	do	46.7	
Aromatics	do	39.7	75

was subjected to steam-cracking under the following conditions:

Temperature ..... ° C 610
 Pressure ..... atm 1
 5 Weight-ratio as feed charge/vapor 11.1
 Space velocity = $4.0 \text{ kg. (feed charge+steam)/h}$
 litres of coil

Space velocity herein means the quantity (expressed as kg.) of feed charge+steam that in a unit of time (hr.) passes through a unit of volume of the cracking coil (expressed as litres).

The outflow was cooled and fractioned in the conventional way. A fraction having a distillation range of from 170-250° C. was obtained containing olefins $C_{10}-C_{14}$.

From 100 parts by weight feed charge, 7.30 parts of said fraction were obtained.

This $C_{10}-C_{14}$ (170-250° C.) had the following composition:

Total olefins:	Percent
n-Olefins	27
Other olefins	35.1
Aromatics	34.9
Paraffins	3.0

25 The yield in normal olefins with respect to the initial charge subjected to cracking was 1.97%

$$(100 \times 0.073 \times 0.27 = 1.97)$$

Then 100 parts of the fraction $C_{10}-C_{14}$ were treated in an autoclave provided with a stirrer and a cooling jacket, and with a quantity of benzene corresponding to a molar-ratio benzene/ $C_{10}-C_{14}$ fraction=6 (the molar ratio, in this and following examples, refers to the average molecular weight of $C_{10}-C_{14}$ fraction) and with anhydrous $AlCl_3$ in the proportion of 5.4 parts by weight $AlCl_3$ to 100 parts of the $C_{10}-C_{14}$ fraction. A current of dry HCl flowed until saturation was reached and the temperature was maintained at 34° C. for 70 minutes. The reaction mixture stratified into two liquid phases which were difficult to separate, the lighter one being formed of excess benzene and of mono- and polyalkylbenzenes, this latter phase, after decantation, washing with an equal volume of water, neutralization with 5% $NaOH$ and subsequent fractioning separated a fraction having a distillation range of from 270°-360° C., and containing the monoalkylbenzenes.

From 100 parts by weight of the fraction $C_{10}-C_{14}$ used for the alkylation, 12.1 parts of monoalkylate were obtained. This meant that from 100 parts by weight of initial charge subjected to cracking about 0.88 part of monoalkylate ($100 \times 0.073 \times 0.121 = 0.88$) were obtained.

An accurate analysis by infrared spectrography determined that the content of alkylbenzenes having linear chain was 32.0% so that the yield of linear monoalkylbenzenes with respect to the starting charge of gasoil was equal to 0.28% ($100 \times 0.073 \times 0.21 \times 0.32 = 0.28$).

50 100 parts of the fraction containing the monoalkylbenzenes were introduced into a reactor provided with a very efficient stirrer (for example, a turbine) and fitted with a suitable cooling system.

To the hydrocarbon, while kept under heavy stirring, were added 108 parts of 104% oleum at such a rate that the temperature inside the reactor did not exceed 30° C. The time required for completing this addition was about 40 minutes.

Upon completion of the addition of oleum, the temperature was brought to 40° C. and stirring was continued for about 120 minutes.

After this time had elapsed, 17.6 parts of water were added at such a rate that the temperature did not exceed 50° C.; generally this took from about 25 to 30 minutes.

Thereupon the stirring was stopped, the mass was transferred into a decanter and left to rest for about 8 hours, bringing the temperature to 20-22° C. In the decanter separation into the two phases took place: the upper one consisting of alkylbenzenesulfonic acid, the lower one consisting of slaked sulfuric acid.

The lower phase was then removed and the upper phase conveyed to a reactor fitted with a slow blade stirrer. Into the same reactor was then introduced a solution of 20% NaOH at such a rate that the temperature did not exceed 50° C. and in such a quantity as would be sufficient to bring the pH of the slurry to about 7 and 9, and preferably between about 7.8 and 9.2.

Generally, about 129-139 kg. of monoalkylbenzenes were needed. The paste obtained had the following average composition:

	Percent
Active substance	45-49
Non-sulfonated	0.7-1.3
NaSO ₄	5.0-10.0
H ₂ O	45-49

The slurry obtained was then dried, powdered and there was added thereto certain additives, so as to obtain a product having the following percentage composition:

	Percent
Active substance (sodium alkylbenzenesulfonate)	25
Sodium sulfate	28
Tripolyphosphate	40
Sodium silicate	5
Carboxymethylcellulose	2

The thus formulated product was then subjected to the German biodegradability test as hereinbefore described. The biodegradability of the detergent, calculated according to this method was less than 50% and, thus, the detergent had to be defined as "nonbiodegradable." The same test was repeated on the non-formulated product consisting merely of sodium alkylbenzenesulfonate, and in this case, also the biodegradability turned out to be lower than 50%.

The product obtained by the method of this example was also subjected to the "River Water Test," the process corresponding to this test is described separately and is common to all the examples given.

Also according to the "River Water Test," the product displayed unacceptable biodegradability. The results of this latter test are recorded directly in Table 2.

The numerical data corresponding to the entire process described in this example are recorded in Table 1, Column 1.

Example 2

A quantity of heavy gas oil, having the same characteristics as the heavy gas oil used in Example 1, was treated to precipitate the wax therefrom by means of a suitable solvent (dichloroethane), using a quantity of solvent with a ratio by weight dichloroethane/gas oil=5:1 at a temperature of -20° C.

A quantity of wax was obtained equal to 19.1% by weight with respect to the quantity of gas oil.

The composition of the wax was as follows:

	Percent
n-Paraffin	31.2
Isoparaffin and cycloparaffin	50.4
Aromatics	18.4

The wax thus obtained was subjected to steam-cracking under the following conditions:

T (temperature)	° C	610
P (pressure)	atg	1.0
Weight ratio of feed charge/steam		11.0

Space velocity=

$$4.1 \frac{\text{kg. (feed charge+steam)/hr.}}{\text{litres of coil}}$$

(as defined in Example 1)

The outflow was cooled and fractionated in conventional manner. A fraction with a distillation range of from

170-250° C. was taken which comprises the C₁₀-C₁₄ olefins.

From 100 parts by weight of wax subjected to cracking, 9.50 parts of said fraction were obtained. The C₁₀-C₁₄ (170-250° C.) had the following composition:

	Total olefins	Percent
n-Olefins		61.2
Other olefins		21.8
Aromatics		14.5
Paraffins		2.5

The yield in n-olefins with respect to the quantity of starting gas oil that had been deoleted with dichloroethane, amounted to 1.11% (100×0.191×0.095×0.612=1.11).

The C₁₀-C₁₄ fraction was then subjected to alkylation with benzene in the same way as described in Example 1, and by using a quantity of benzene with a molar ratio benzene/C₁₀-C₁₄ fraction equal to 6.1, a quantity of anhydrous AlCl₃, in amounts of 3.6 parts by weight of AlCl₃ per 100 parts of C₁₀-C₁₄ fraction, and the other values (temperature, time, etc.) remaining unchanged.

After separation and fractioning a fraction was obtained having a distillation range of from between about 270-360° C. and containing monoalkylbenzenes in amounts of 83.2 parts by weight of monoalkylbenzenes per 100 parts of the C₁₀-C₁₄ fraction used in the alkylation.

This meant that from 100 parts by weight of the starting gas oil there was obtained 1.50 parts of monoalkylbenzenes (100×0.191×0.095×0.832=1.50).

An accurate analysis through infrared spectrography test established that the content of alkylbenzenes having linear chains amounted to only 68.5% of the product obtained.

That is, from 100 parts by weight of the starting gas oil there was obtained 1.03 parts monoalkylbenzene with linear chains (1.50×0.685=1.03).

The product, sulfonated and formulated under similar conditions as those described in Example 1, displayed a biodegradability of lower than 50% as determined according to the aforesaid German test.

Similar to that described in the preceding example the same test was carried out on the non-formulated alkylbenzenesulfonate and a negative result was also obtained.

Also and according to the second "River Water Test," the product likewise exhibited insufficient biodegradability; the results of this latter test are directly recorded in Table II.

The numerical data for process described in this example are recorded in Table 1, Column 2.

Example 3

A definite quantity of heavy gas oil obtained from the vacuum distillation of the topping residue from Lybian crude oil and having the following characteristics:

Distillation range	° C	440-580
Refraction index N _D ²⁰		1.4820
Composition:		

n-paraffins	percent	14.7
isoparaffins and cycloparaffins	do	54.4
Aromatics	do	31.9

was treated to precipitate the wax therefrom by means of a polar solvent (methyl ethyl ketone).

Thereby a quantity of wax was obtained equal to a 22.2% by weight with respect to the quantity of gas oil.

The composition of the wax was as follows:

	Percent
n-Paraffins	33.8
Isoparaffins and cycloparaffins	58.5
Aromatics	7.7

The wax thus obtained was subjected to steam-cracking under the following conditions:

Temperature $^{\circ}\text{C}$ 610
Pressure atg 1
Weight ratio feed charge/steam 11.0 5

Space velocity =

$\frac{\text{kg. (feed charge+steam)/hr.}}{\text{litres of coil}}$

(as defined in Example 1)

The outflow was cooled and fractioned in conventional manner.

A fraction with a distillation temperature range from 170°–250° C. was taken, which was comprised of C_{10} – C_{14} olefins. From 100 parts by weight of wax subjected to cracking, there was obtained 10.70 parts of said fraction, while, with respect to 100 parts of starting gas oil, the quantity of said fraction amounted to 2.37 parts by weight ($100 \times 0.222 \times 0.107 = 2.37$).

The C_{10} – C_{14} fraction (with a distillation range of from 170–250° C.) displayed the following composition:

Total olefins:	Percent
n-Olefins	68.6
Other olefins	20.9
Aromatics	4.0
Paraffins	6.5

The quantity of n-olefins obtained from 100 parts by weight of starting gas oil amounted to 1.62 parts by weight ($100 \times 0.222 \times 0.107 \times 0.686 = 1.62$).

The C_{10} – C_{14} fraction (170–250° C.) was subjected to alkylation with benzene in the same manner as described in Example 1, and by using a quantity of benzene equal to a molar ratio of benzene/ C_{10} – C_{14} fraction equal to 6.1, a quantity of anhydrous AlCl_3 equal to 3.3 parts by weight of AlCl_3 for 100 parts of C_{10} – C_{14} fraction used in the alkylation, and by maintaining the temperature at 33° C. for 60 minutes.

After separation and fractioning, a fraction was obtained having a distillation range of from 270°–350° C. and containing monoalkylbenzenes at a rate of 93.4 parts by weight of monoalkylbenzenes for 100 parts of the C_{10} – C_{14} fraction used in the alkylation.

An accurate analysis by means of an infrared test determined that the content of alkylbenzenes having linear chains was equal to 71.0% of the monoalkylate obtained.

On the whole, for 100 parts by weight of starting gas oil, 2.22 parts of monoalkylate ($100 \times 0.222 \times 0.107 \times 0.934 = 2.22$) and 1.57 parts of linear monoalkylate ($2.22 \times 0.71 = 1.57$) were obtained.

The product, sulfonated and formulated under conditions similar to those described in Example 1, exhibited according to the aforesaid German test a biodegradability of less than 50%. This is an absolutely unacceptable biodegradability rate.

The same test was repeated on the non-formulated product, consisting merely of sodium alkylbenzenesulfonate, but in this case also the biodegradability was less than 50%.

The pure product i.e. the non-formulated alkylbenzenesulfonate was also subjected to the "River Water Test." The process concerning this test is described separately since it is common to all the given examples and the results are recorded on Table II.

Also according to the "River Water Test" the product displayed a biodegradability that was unacceptable. The results of this latter test are directly recorded in Table II.

The numerical data of the full process described in this example are recorded on Table 1, column 3.

vacuum distillation of the topping residue of a Lybian crude and having the following characteristics:

Distillation temperature range $^{\circ}\text{C}$ 400–500
Refraction index N_D^{20} 1.4835
Composition:

n-Paraffins	percent	13.7
Isoparaffins+cycloparaffins	do	48.2
Aromatics	do	38.1

was treated by partial melting, filtering and subsequent refining with methyl ethyl ketone.

A quantity of wax was obtained equal to 16% by weight with respect to the quantity of gas oil. The wax obtained displayed the following composition:

n-Paraffin	Percent	53.7
Isoparaffins+cycloparaffins	do	42.2
Aromatics	do	4.1

The wax thus obtained was subjected to steam-cracking under the following conditions:

T (temperature) $^{\circ}\text{C}$ 610
P (pressure) atg 1.0
Weight ratio feed charge/steam 11.0

Space velocity =

$\frac{4.1 \text{ kg. (feed charge+steam)/hr.}}{\text{litres of coil}}$

(defined as in Example 1)

The outflow, cooled and fractioned in conventional manner. A fraction was obtained with a distillation range of from 170°–250° C. and comprising the C_{10} – C_{14} olefins. From 100 parts by weight of wax, 9.0 parts of said fraction were obtained, while, with respect to 100 parts by weight of the starting gas oil, the quantity of said fraction amounted to 1.44 parts ($100 \times 0.16 \times 0.09 = 1.44$).

The C_{10} – C_{14} fraction (170°–250°) had the following composition:

Total olefins:	Percent
n-Olefins	71.5
Other olefins	22.3
Aromatics	3.0
Paraffins	3.2

The quantity of n-olefins obtained from 100 parts by weight of the starting gas oil was 1.03 parts ($100 \times 0.16 \times 0.09 \times 0.715 = 1.03$).

The C_{10} – C_{14} fraction was subjected to alkylation with benzene by operating the same way as is described in Example 1 and by using a quantity of benzene with a molar ratio benzene/ C_{10} – C_{14} fraction = 6.0, a quantity of anhydrous AlCl_3 equal to 3.3 parts by weight of AlCl_3 for 100 parts of the C_{10} – C_{14} fraction used in the alkylation, and by maintaining the temperature at 32° C. for 70 minutes.

After separation and fractioning, a fraction with a distillation range of from 270°–360° C. was obtained that contained C_{16} – C_{20} monoalkylbenzenes at the rate of 97.0 parts by weight of monoalkylbenzenes for 100 parts of C_{10} – C_{14} fraction used in the alkylation.

The infrared spectrographic analysis revealed a content of alkylbenzenes having linear chains equal to 74% by weight of the total monoalkylbenzenes obtained. From 100 parts by weight of gas oil one obtained therefore 1.40 parts of monoalkylate ($100 \times 0.16 \times 0.09 \times 0.97 = 1.40$) of which 1.03 parts were monoalkylate having a linear chain ($1.40 \times 0.74 = 1.03$).

The monoalkylate, sulfonated and formulated under the same conditions as those described in Example 1 displayed a biodegradability as determined according to the German test, of less than 50%.

The same test was carried out on the non-formulated product consisting solely of sodium alkylbenzenesulfonate

Example 4

A certain quantity of heavy gas oil obtained from the

11

and in this case also the biodegradability was lower than 50%.

The pure product, i.e., the non-formulated alkylbenzenesulfonate, was also subjected to the "River Water Test" and according to this method, the result was also negative. The results of the "River Water Test" are directly recorded in Table II.

The numerical data of the full process described in this example are recorded in Table 1, Column 4.

Example 5

A certain quantity of heavy gas oil, having the same characteristics at the gas oil used in Example 1, was treated with urea to isolate the n-paraffins according to the following procedure:

Into a mixer or other vessel fitted with a very efficient stirrer were introduced 130 litres of H_2O and the temperature was brought to 40° C. Then, under vigorous stirring, 350 kg. of urea and 160 kg. of methylisobutylketone were added. Upon completion of this addition, still under stirring, 100 kg. of heavy gas oil were introduced into the mixer and the temperature was gradually brought down to 22°–20° C. in 30 minutes.

Thereupon the adduct thus formed was separated by filtration from the urea solution and the methylisobutylketone.

The crystals of the adduct were then mashed into about an equal quantity by weight of methylisobutylketone, filtered again, and then dried in order to completely eliminate the solvent.

The adduct was then decomposed with water at a temperature of from about 60°–80° C.

The oily phase, consisting for the most part of the paraffins which had formed the adduct with the urea, was then separated from the urea solution (which may be recycled) weighed 18 kg. and had the following composition:

	Percent
n-Paraffins	71.0
Isoparaffins+cycloparaffins	25.1
Aromatics	3.9

The wax thus obtained was subjected to steam cracking under the following conditions:

Temperature	° C.	610
Pressure	atg.	1
Weight ratio of feed charge/steam		11.0

Space velocity=	50
4.0 kg. (feed charge+steam)/h.	
litres of coil	

(defined as in Example 1)

The outflow was then cooled and fractioned in conventional manner. A fraction was obtained having a distillation temperature range of from 170°–250° and containing the C_{10} – C_{14} olefins.

From 100 parts by weight of wax subjected to the steam cracking, there were obtained 9.90 parts of said fraction, while, with respect to 100 parts by weight of the starting gas oil, the quantity of said fraction amounted to 1.78 parts ($100 \times 0.18 \times 0.099 = 1.78$).

The C_{10} – C_{14} (170°–250° C.) fraction displayed the following composition:

Total olefins:	Percent
n-Olefins	83.7
Other olefins	12.3
Aromatic	1.70
Paraffins	2.3

The quantity of n-olefins obtained from 100 parts by weight of starting gas oil amounted to 1.49

$$(100 \times 0.18 \times 0.099 \times 0.837 = 1.49)$$

12

Said fraction was then subjected to alkylation with benzene following the same procedure as described in Example 1 under the following conditions:

5	Molar ratio benzene/ C_{10} – C_{14} fraction	6.0
5	Temperature	° C.
5	Time	minutes
5	Quantity by weight of anhydrous $AlCl_3$ for 100 parts of C_{10} – C_{14} fraction	2.8

10 After separation and fractioning was obtained having a distillation temperature range between 270° and 360° C. and containing C_{16} – C_{20} monoalkylbenzenes at the rate of 100.0 parts by weight of monoalkylbenzenes for 100 parts of the C_{10} – C_{14} fraction used in the alkylation.

15 An accurate infrared spectroscopic analysis determined the content of linear chain alkylbenzenes to be 85% of the monoalkylate obtained.

On the whole, for 100 parts by weight of starting gas oil, 1.78 parts of monoalkylate and 1.51 parts (1.8×0.85) of monoalkylate containing linear chain alkylbenzenes were obtained.

20 The product, after sulfonation and formulation under the same conditions as those described in Example 1, showed a biodegradability equal to 78% as determined according to the aforesaid German test.

25 Similarly to that described in Example 1, the same test was also carried out on non-formulated alkylbenzenesulfonate, and there was also obtained an unsatisfactory result.

30 The pure product, i.e. the non-formulated alkylbenzenesulfonate was also subjected to the "River Water Test." The results of this method were not altogether satisfactory. The results of the "River Water Test" are directly recorded in Table II.

35 The numerical data of the entire process described in this example are recorded in Table 1, column 5.

Example 6

40 A certain quantity of heavy gas oil, having the same characteristics as the gas oil used in Example 1, was subjected to steam-cracking under the following conditions:

Temperature	° C.	610
Pressure	atg.	1
Weight ratio feed charge/steam		11.1

45 Space velocity=

$$4.0 \frac{\text{kg. (feed charge+steam)/h.}}{\text{litres of coil}}$$

(defined as in Example 1)

50 The outflow was then cooled and fractioned in conventional manner and a fraction with a distillation range of from 170°–250° C. and comprising the C_{10} – C_{14} olefins was separated therefrom.

55 From 100 parts by weight of gas oil there were obtained 7.30 parts of the above fraction. The C_{10} – C_{14} fraction (170°–250°), displayed the following composition:

Total olefins:	Percent
n-Olefins	27.0
Other olefins	35.1
Aromatics	34.9
Paraffins	3.0

60 The yield in n-olefins with respect to the starting charge subjected to steam-cracking amounted to 1.97%

$$(100 \times 0.073 \times 0.27 = 1.97)$$

65 100 kg. of the C_{10} – C_{14} fraction were treated in a mixer or other apparatus affording intimate contact between a solid and a liquid phase with 120 kg. of urea and 110 litres of a mixture of methanol/hydrocarbons in a volumetric ratio of 20:1, at a temperature of 20° C., and with continuous stirring. The hydrocarbons used in the mixture with the methanol were hydrocarbons with a non-linear chain having a distillation range of from 60°

to 180° C.; they were used with the purpose of promoting the mixing.

After 30 minutes the solid mass (adduct of the urea with n-olefins) comprising iso- and cycloolefins and aromatics, was separated from the oily mass, and from the methanol through filtering (centrifugation). The methanol, containing 10 kg. of dissolved urea, was separated by decantation and could be utilized in other charges without further treatment. From the oil the methanol dissolved by distillation was recovered.

The adduct (143 kg.) was then suspended in 100 kg. of anhydrous benzene and then filtered or centrifuged. The recovered benzene could be used just as it was for the washing of the subsequent charges, or could be immediately purified by distillation. The solid filtrated mass was then suspended in 72 kg. of anhydrous benzene and brought to 65° C. for 30 minutes, under constant stirring and the adduct decomposed with quantitative separation of the urea. The urea (110 kg.) was then decanted and could be used without further manipulations in successive operations.

The determination of the yield of the extraction with urea and the quality of the n-olefins were determined using a small fraction of the liquid, from which the urea had been separated according to the following procedure: 100 g. of the mixture were subjected to fractional distillation until the benzene was wholly eliminated: the residue was weighed and analyzed by mass and by infrared spectrography. From 100 g. of C₁₀–C₁₄ fraction containing 27 parts by weight n-olefins there were obtained 25.8 parts by weight of olefins (residue) with a content of n-olefins equal to 98.4% by weight.

In other words, the extraction yield based on the normal olefins contained in the C₁₀–C₁₄ fraction was equal to

$$\frac{25.8 \times 0.984}{27.0} \times 100 = 94.1$$

and the yield based on the starting gas oil was equal to

$$100 \times 0.073 \times 0.27 \times 0.941 = 1.85$$

The liquid, consisting of benzene containing dissolved olefins, and from which the urea had been separated, was brought to 33° C. and then subjected to alkylation in the same manner as that described in Example 1. The molar ratio benzene/C₁₀–C₁₄ purified fraction was equal to 6.0.

In this case, only 0.62 kg. of AlCl₃ (i.e. only 2.4 parts with respect to 100 parts of purified C₁₀–C₁₄ fraction) were required to complete the reaction. The alkylation temperature was 33° C. for a period of 60 minutes.

The alkylated liquid was then decanted, washed and neutralized, and was then fractioned in the same way as that described in the preceding examples. A fraction was obtained having a distillation range of from 270–360° C. and containing the monoalkylbenzenes.

From 25.8 parts by weight purified linear olefins subjected to alkylation there were obtained 26.5 parts of monoalkylbenzenes, i.e., a quantity equal to 103% by weight.

The yield of monoalkylbenzenes based on starting charge of heavy gas oil was equal to 1.93 parts by weight for 100 parts (100 × 0.073 × 0.258 × 1.03 = 1.93). Analysed by means of very accurate infrared spectrography, the above fraction revealed a content of linear alkylbenzenes equal to 98.6%, wherefore the yield in linear monoalkylbenzenes was the highest with respect to the preceding examples and equals 1.90 by weight based on the starting charge of heavy gas oil

$$(100 \times 0.073 \times 0.258 \times 1.03 \times 0.986 = 1.90)$$

The above mentioned fraction containing the monoalkylbenzenes was sulfonated, etc., and there was added

thereto all the various additives according to the formulation used in Example 1.

The product thus prepared was then subjected to the biodegradability test according to the aforesaid German test and exhibited an actual biodegradability of 97%.

The same test was repeated on the non-formulated product, consisting solely of sodium alkylbenzenesulfonate.

In this case also the biodegradability was very high.

Also, according to the "River Water Test," the product exhibited excellent biodegradability, the results of this latter test being directly recorded in Table II.

The numerical data of the complete process described in this example are recorded in Table 1, Column 6.

15

Example 7

In a preferred form of execution, a fraction of gas oil of high boiling point, having a distillation range of from 350°–550° C. and having the same characteristics of the gas oil used in Example No. 1, was subjected to steam cracking under the following conditions:

Temp.	----- ° C	640
Pressure	----- atm	1.0
Weight ratio feed charge/steam	-----	10.8
Space velocity = 4.9 kg. (feed charge+steam)/hr.	----- litres of coil	
	(defined as in Example 1)	

30

The outflow was cooled and fractioned in conventional manner and there was obtained therefrom a fraction having a distillation range of from 170°–250° C. and containing the C₁₀–C₁₄ olefins.

35

From 100 parts by weight of gas oil there were obtained 8.9 parts of the said fraction having the following composition:

Total olefins:	Percent
Normal olefins	28.5
Other olefins	35.5
Aromatics	33.5
Paraffins	2.5

45

The yield in n-olefins based on the charge was 2.54% (100 × 0.089 × 0.285 = 2.54).

50

100 kg. of the fraction containing the C₁₀–C₁₄ olefins were treated with urea in similar manner as described in Example 6, but using 125 kg. of urea and 110 litres of a methanol/hydrocarbons mixture consisting of 104 litres of methanol and of 6 litres of hydrocarbons (these hydrocarbons consisted of a mixture of residual oils from preceding extraction of the n-olefins). One proceeded as in Example 6 until the adduct was decomposed and the urea was separated, the yield of the extraction with urea was then determined, as well as the quality of the extracted olefins, still according to the method described in Example 6.

55

From 100 parts by weight of C₁₀–C₁₄ fraction containing 28.5 parts of n-olefins, 27.15 parts of olefins (residue) were obtained, which after analysis by mass and infrared spectrometry, revealed a contents of n-olefins equal to 97.6% by weight.

The extraction yield based on the olefins contained in the C₁₀–C₁₄ fraction was 93.0%

65

$$\left(\frac{27.15 \times 0.976}{28.5} \times 100 = 93.0 \right)$$

70

and the contents based on the heavy starting gas oil was 2.36% (100 × 0.089 × 0.285 × 0.93 = 2.36).

The liquid, consisting of benzene containing the dissolved olefins, and from which the urea had been separated, was brought to 32° C. and then subjected to alkylation in the same manner as described in Example 1;

the molar ratio benzene/C₁₀—C₁₄ purified fraction was equal to 6.1. Also, in this case only 0.62 kg. of AlCl₃ (that is, only 2.4 parts based on 100 parts of purified C₁₀—C₁₄ fraction) were eventually necessary for completing the reaction. The alkylation temperature was 32° C. 5 for a period of 60 minutes.

Thereupon, the alkylated liquid was decanted, washed and neutralized, and then fractionated in the same manner as described in the preceding examples.

From 100 parts by weight of purified linear olefins 10 there were obtained 100.2 parts of monoalkylbenzenes (isolated fraction having a distillation range of from 270°—360° C.) with a yield, based on the starting heavy gas oil charge of 2.42% (100×0.089×0.2715×1.002=2.42) that is, about 25% more than that of Example 6, and 15 35% more than that of Example 5.

An accurate analysis by infrared spectrography revealed a content of monoalkylbenzenes having linear chains of 98.5%, thus bringing the yield of monoalkylbenzenes of linear chain to 2.38 parts in a hundred based on the starting gas oil. 20

The fraction containing the monoalkylbenzenes was then sulfonated, etc., and there was added thereto the various additives according to the formulaion used in Example 1. The product thus prepared was subjected to 25 the biodegradability test according to the aforesaid German test and revealed a biodegradability of 96.4%.

The same test was repeated on the non-formulated product, consisting merely of sodium alkylbenzene sulfonate.

In this case also the biodegradability was very high.

Also, according to the "River Water Test," the product displayed an excellent biodegradability. The results of this latter test being recorded in Table II.

The numerical data of the entire process as described 35 in this example are recorded in Table I, column 7.

CONTROL OF THE BIODEGRADABILITY ACCORDING TO THE METHOD OF THE "RIVER WATER TEST"

All the products obtained according to the methods described in Examples 1 to 7 were subjected, as mentioned in the examples themselves, to the "River Water

5 sponding to the different analyses are recorded in Table II.

From the examination of the values obtained it can be inferred that according to the "River Water Test" also the alkylbenzenesulfonate obtained according to the process of this invention (see columns corresponding to Examples 6 and 7) exhibits the greatest biodegradability.

TABLE II

Samples	Na alkyl-benzene sulfonate from tetra-propylene	Example						
		1	2	3	4	5	6	7
Initial conc. in p.p.m.	9.8	9.7	10.2	10.3	9.9	10.1	10.3	10.2

Test" in order to check the biodegradability according to 25 this method.

The control procedure according to this method is common to all examples with respect to the quantity of the substances used and with respect to control times, wherefore it will be described hereinafter and will be valid for 30 all examples.

The results obtained are recorded in Table II.

For this purpose, the pasty masses obtained through neutralization of the alkylbenzenesulfonic acids (obtained by sulfonation of the fraction of $C_{16}-C_{20}$ monoalkylbenzenes) were accurately purified from the sodium sulfate and then dried. This process was carried out separately for each example.

The purified sodium alkylbenzenesulfonates corresponding to the seven examples were introduced separately to glass vessels containing river water in such quantity as to have an initial concentration equal to about 10 p.p.m.; the concentration was checked with methylene blue.

The glass vessels were locked and the solutions stored at room temperature.

In another vessel a comparative solution was prepared following the same procedure, i.e. a solution of commercial sodium alkylbenzenesulfonate obtained from tetrapropylene (10 p.p.m.) The eight solutions are analyzed periodically according to the methylene blue method. The concentration of the product corresponding to each example was compared with the concentration of the alkylbenzenesulfonate derived from tetrapropylene. The values of the various concentrations and the time intervals corre-

40 sponding to the different analyses are recorded in Table II. From the examination of the values obtained it can be inferred that according to the "River Water Test" also the alkylbenzenesulfonate obtained according to the process of this invention (see columns corresponding to Examples 6 and 7) exhibits the greatest biodegradability.

45 What is claimed is:

1. In a process for the production of olefins suitable for conversion to detergent alkylates via the cracking of heavy petroleum fractions, the fractional distillation of the fraction thus-cracked and the separation therefrom of a fraction rich in straight-chain olefins, the improvement which comprises the cracking of a heavy petroleum fraction boiling within the range of from about 300° C. to 600° C. and containing more than about 35% by weight aromatics and less than about 15% by weight straight-chain hydrocarbons, the separation therefrom of a second fraction rich in straight-chain olefins having from 8 to 15 carbon atoms and having a distillation range of from about 120° C. to 300° C., and the recovery of such straight-chain olefins having from 8 to 15 carbon atoms from said second fraction by treating the same with urea to selectively form adducts of urea with said olefins, separating these adducts and thence decomposing the same.

50 2. The process as defined by claim 1, wherein the selective formation of adducts of urea with olefins is effected by treating the said second fraction with an alcoholic urea solution having from 3.5 to 5 parts by weight urea with respect to one part by weight of straight-chain olefins and having 0.5 to 1.2 parts by weight alcohol with respect to one part by weight urea.
